UNITED STATES PATENT OFFICE.

WILLIAM WAGNER, OF WASHINGTON, DISTRICT OF COLUMBIA.

CARTRIDGE-CRIMPER.

SPECIFICATION forming part of Letters Patent No. 549,553, dated November 12, 1895.

Application filed September 13, 1895. Serial No. 562,389. (No model.)

To all whom it may concern:

Be it known that I, WILLIAM WAGNER, of the city of Washington, District of Columbia, have invented certain new and useful Improvements in Cartridge-Crimpers; and I do hereby declare the following to be a full, clear, and exact description of the invention, such as will enable others skilled in the art to which it appertains to make and use the same.

10 My invention, while relating chiefly to improvements in cartridge-crimping heads, also involves improvements in the actuating mechanism of cartridge-crimpers.

In the operation of devices of a class to which 15 my improvements in crimping-heads are applicable the ends of shells to be crimped are inserted into tubular portions or receivers of the crimping-heads, which are provided with suitable inside projections for turning inward 20 the ends of the shells, and with spring-actuated followers, between which and the receivers the ends of the shells are supported with the followers yieldingly bearing against the top or shot wads in the shells during crimping, 25 so as to insure the seating of the wads upon the shot.

Objects which I have most particularly in view are to increase the durability of crimping-heads, to adapt them to produce perfect 30 crimps, and to prevent bulging, buckling, or other distortion of the shells crimped.

To produce perfect crimps and avoid distorting the shells, the end of each shell operated upon should snugly fit within the receiver 35 around the follower of the crimping-head or substantially correspond in diameter with the internal diameter of the receiver not only at the plane of a line drawn transversely through the receiver and touching or close to 40 the advance surfaces of the crimping projections, but also forward of this plane, or toward the outer end of the receiver, for a distance at least equal to the length of the crimp.

A serious defect in heretofore-employed 45 crimping-heads, in each of which the shell-engaging portion of the receiver is designed to be of substantially-unvarying length throughout use, is that when much used they become unreliable or useless by the wearing away and 50 enlargement in internal diameter of the receivers, resulting from frictional contact with the shells, and the wearing away of the crimp-

ing projections by excessive frictional contact with the shells unfits the crimpers for use unless provision is made for the renewal of such 55 projections. Even when, as in an old form of crimping-head, in which detachable pins constitute the crimping projections, provision is made for substituting one set of pins for another, the defect arising from the repeated 60 wear upon the same surface of the receiver—the shell-engaging portion thereof of practically unvarying length—still exists. Another defect in crimping-heads provided with spring-actuated followers as usually constructed 65 is that their action on the shells may be prolonged injuriously by continuing their rotation after the shells have been sufficiently turned in at their ends to properly crimp them, with the result that as the followers continue 70 to yield the turned-in ends of the shells are spread out or forced toward the centers of the wads, producing unsightly crimps, bulging 75 the wads, and sometimes distorting the shells so badly as to unfit them for use.

Now, in accordance with my improvements, I provide a crimping-head so constructed that the crimping projections may readily be reshaped or renewed and kept in proper working condition, and so that as wear and reshaping of these projections increase their distance from the end of the receiver into which the shells project new or additional portions of the receiver are brought into use to snugly embrace and properly support the 80 shells in crimping, while extending the surface subjected to wear by frictional contact with the shells. I also provide for limiting the yielding movement of the follower to prevent excessive and injurious crimping action, 85 and, further, I provide for the reversing of parts to adapt them to act at either end, in order that when objectionable wear occurs at one end the other end may be brought into use. These and other features of my im- 90 provements will hereinafter fully be explained and the subject-matter deemed novel 95 specifically claimed.

In the accompanying drawings, which show a crimping-head with my improvements and improved mechanism suitable for actuating it, Figure 1 is a view in side elevation showing the crimping-head with the actuating mechanism; Fig. 2, a view in front elevation

showing the actuating mechanism modified; and Fig. 2^a a view in elevation, on a reduced scale, of the adjustable foot-rest or stirrup and the chain connecting it with the pull-rod 5 of the actuating mechanism. Fig. 3 shows in vertical central section, on a larger scale than the preceding views, the crimping-head and the carrier therefor of the actuating mechanism; and Figs. 4, 5, and 6 are views in 10 perspective showing, respectively, the crimping-head, the detachable section thereof formed with end crimping projections, and the follower of the crimping-head, these 15 views being on a scale somewhat larger than Fig. 3.

A sectional crimping-head which is capable of being used in connection with a suitable lathe, in the chuck of which it may be secured, or with any appropriate actuating 20 mechanism operated manually or by power is shown constructed as follows: A cartridge-receiver or outer tubular section A of cylindrical form has its bore flared or tapered at its ends to facilitate the entrance into it 25 of the ends of cartridge-shells the external diameters of which correspond substantially with the internal diameter of the receiver for nearly its entire length or between its flaring ends. A hole a is made through the 30 receiver midway its length. A tubular inner section B of the crimping-head is formed to nicely fit within the outer section or receiver and has a hole b through it midway its length to register with the hole in the receiver, so that 35 a readily-removable pin C may serve to detachably connect the two sections. The section B is provided with crimping projections B' of any suitable number at its opposite ends, formed in one piece or integral there- 40 with by suitably scalloping it. The projections are properly tapered or rounded off at their extremities and are made of proper length by the formation of the notches b' between them to most efficiently perform their 45 function. By filing or cutting away at the notches b' and otherwise properly reshaping the projections when worn by use the section B of the crimping-head may successfully be employed until entirely used up, as farther 50 on will more plainly be made apparent.

A spring-actuated follower D of the crimping-head of a diameter substantially corresponding with the internal diameter of the end 55 of a shell when doubled or crimped is shown as closed or solid at its outer end and tubular for the remainder of its length. It has diametrically-opposite elongated slots d in its sides, through which passes the pin C for detachably connecting the follower with the 60 outer and inner crimping-head sections A and B. The spring D' within the follower and bearing at its opposite ends against the follower-head and the connecting-pin C exerts a yielding pressure upon the follower to 65 advance or thrust it outward to the extent of its movement in such direction, which is limited by contact with the cross-pin of the shoul-

ders formed by the walls of the slots d at their inner ends. Inward movement of the follower when its spring yields to pressure 70 upon the follower-head is limited by contact with the cross-pin of the shoulders formed by the walls of the slots d at their outer ends.

The receiver, the section formed with the crimping projections, and the follower are 75 preferably made of suitable steel, so as to resist wear to the maximum extent.

In operation, the crimping-head being mounted in a lathe-chuck or properly supported by any suitable actuating mechanism 80 so as to be rotated and appropriate means being provided for supporting loaded shells so as to be acted upon by the crimping-head, it will be understood that when a shell's end is inserted into the receiver of the rotating 85 crimping-head and pressed against the crimping projections to crimp it while the follower bears against the shot-wad that portion of the shell which is doubled or crimped will snugly fit or fill the space between the 90 receiver and follower and is properly supported, while by positively arresting the inward movement of the follower at about the time that a perfect crimp has been formed, at which time the stop provided by the walls 95 of the follower-slots comes in contact with the connecting-pin, further movement of the shell into the receiver is prevented and it becomes impossible to continue the crimping action upon the shell to an injurious extent. As 100 the crimping projections gradually wear way, (they wear much more rapidly than the receiver wears where it comes in contact with the shells,) the shells are allowed to project farther and farther into the receiver, thus 105 being brought into contact with and supported by new or unworn portions of the receiver and snugly embraced. The inner section 110 of the crimping-head may quickly be separated from other parts and again readily connected with them after reshaping the crimping projections, this inner section becoming 115 gradually shorter as wear progresses and it is filed away in reshaping the projections, and the distance the shells are allowed to project 120 into the receiver correspondingly increasing until the inner section has been entirely used up, after which a new inner section may be employed with the same receiver the wear upon which is obviously slight as compared 125 with that upon the crimping projections, as the surface of the receiver which is subjected to wear by the shells is much greater than the wearing-surfaces of the crimping projections and is being repeatedly added to in use. Thus new inner sections may be successively employed indefinitely, or until appreciable 130 and injurious wear of the receiver may result from long use. As the crimping projections are worn away and the inner section of the crimping-head shortened, while the distance the shells enter into the receiver is correspondingly increased, the slots in the follower are properly lengthened by filing away

their walls at the outer ends, so that the inward movement of shells in crimping will not be arrested until at the proper time to prevent injurious crimping action. The follower 5 being connected with the receiver, and inner section of the crimping head by the detachable connecting-pin may readily be removed and replaced.

When the receiver and the section provided 10 with crimping projections are made reversible, to adapt them to be turned end for end, so as to operate at either end, (I prefer to so construct them, although this feature of reversibility may be omitted in one or both 15 parts,) it will be seen that after injurious wear takes place at one end of the parts they may quickly be reversed and used without the delay of reshaping or renewing the projections.

My improved crimping-head may be modified 20 in various respects, and still retain important features of my invention. Among modifications which may readily be made are the following:

Instead of the long or through-pin C for 25 connecting the parts, there may obviously be provided a shorter connecting-pin having a nicked or screw head and a thread for a portion of its length adjacent to its head to engage a thread in the hole a, which may be 30 formed through one side only of the receiver. The unthreaded portion of this form of connecting-pin would pass through the hole b, which may be formed in one side only of the section having the crimping projections, and 35 through one of the slots d (the other slot might be omitted) in the follower and extend across or far enough into the follower to serve as a bearing for one end of its spring.

By the employment of the reversible inner 40 section it is obvious that its projections at one end may be shaped to form what is termed a "square" crimp and those at the other end adapted to form a so-called "round" crimp.

The actuating mechanism shown by the 45 drawings is adapted to be clamped at the base E of its frame to a bench or table in suitable way, and is provided with a socket or fixed holder F for the bases of the shells to be crimped. A standard G of the frame serves 50 as a support and guide-way for a carrier H in a bearing in which the crimping-head is mounted to rotate, and which is movable up and down this standard. The frame standard projects upwardly from the frame-base in rear 55 of the shell-holder, and is suitably embraced by the rearwardly-projecting portion or horizontal arm of the carrier, so that up-and-down movement may be imparted to the carrier, the bearing in which for the crimping-head is over 60 the shell-holder F, provided in the base of the frame. The outer section or receiver of the crimping-head is provided with an annular groove h, (two such grooves are provided when the receiver is of the preferred reversible construction, as shown,) into which projects the unthreaded end of a screw J, passing through

one side of the bearing in the carrier, for properly engaging the crimping-head with this bearing, while leaving the head free to rotate. In accordance with the construction 70 shown in Figs. 1 and 3 the crimping-head is rotated in its bearing in the carrier by means of a crank-handle K, rotating horizontally and fastened to the stud or boss k of a cap or collar L, secured to one end of the receiver of 75 the crimping-head by a screw M, which projects through one side of the cap and engages a hole in the receiver. As shown in Fig. 2, instead of rotating the crimping-head directly by a crank gearing intermediate the crank 80 and crimping-head is employed, and the crank rotates vertically or about a horizontal axis, the crank being attached to a driving bevel-gear N, which rotates about a stud provided at the side of the carrier-bearing for the 85 crimping-head. This driving-gear meshes with the driven gear O, suitably secured to the receiver of the crimping-head. To move the carrier H up and down, a pull-rod P is attached at its upper end to the carrier and extends downwardly through the frame-base, which is provided with openings p p, constituting bearings for the pull-rod to reciprocate in. These bearings maintain the pull-rod in 90 an upright position and adapt it to assist in supporting the carrier against horizontal vibration or lateral movement about the frame standard, so that the carrier and consequently the crimping-head is always kept in proper alignment with shells in the holder. A 95 spring Q about the pull-rod and bearing at its opposite ends against the frame-base and the reciprocating carrier serves to yieldingly uphold the carrier and to restore it to its normal or most elevated position after being moved 100 downward. Upward movement of the pull-rod is arrested at the proper time by contact with the frame-base of its enlarged lower end or bent portion q. To move the carrier downward by its pull-rod and force the crimping- 105 head into operative contact with the end of a shell to be crimped, suitable means for readily moving the pull-rod against the force exerted by its spring are provided, so that either the hand or foot of the operator may be used, 110 as preferred, for the purpose. To move the carrier downward by the foot, a chain R is shown as attached to the eye formed at the lower end of the pull-rod, and a tubular foot-rest S, adapted to slide on the chain, provides 115 for forming a stirrup at any desired distance below the pull-rod. The chain is looped, with the foot-rest supported at the bottom of the loop, the free end of the chain being linked to that portion of it above the foot-rest at any 120 desired point, as will readily be understood. To operate the pull-rod by hand, a lever T, having jointed connection at one end with the under side of the frame-base, provided with a handle at its opposite end, and passing 125 through the eye of the pull-rod, may be employed, as plainly shown by Fig. 1.

The operation of the above-described actuating mechanism will be apparent without further explanation.

I claim as my invention—

- 5 1. The sectional crimping head having the outer section or shell-receiver, and the inner section detachably secured to said receiver and formed with end crimping projections, substantially as set forth. 45
- 10 2. In a cartridge crimping head the reversible receiver flared at both ends to adapt it for adjustment to receive the shells at either end, in combination with suitable crimping projections, substantially as set forth. 50
- 15 3. The combination of the outer section or receiver of the crimping head, and the reversible inner section detachably secured to said receiver and formed with crimping projections at its opposite ends, substantially as set forth. 55
- 20 4. The combination of the outer section or receiver of the crimping head flared at both ends to adapt it to receive the shells at either end, and the inner section formed with crimping projections at both ends, substantially as set forth. 60
- 25 5. The combination of the outer section or receiver of the crimping head, the inner section detachably connected with said receiver and having end crimping projections formed integral with it, and the detachably connected spring-actuated follower movable within said inner section, substantially as set forth. 65
- 30 6. The combination of the outer section or receiver of the crimping head, the inner section formed with the end projections, the slotted spring-actuated follower, and the pin engaging the slotted portion of the follower and detachably connecting the parts, substantially as set forth. 70
- 35 40

7. The combination of the frame provided with the shell holder and having the upwardly projecting standard, the carrier movable up and down said standard, the pull-rod connected to the carrier and extending through the frame base, means for actuating the pull-rod to move the carrier downwardly, the spring for elevating and yieldingly upholding the carrier, the crimping head supported by the carrier, and means for rotating the crimping head, substantially as set forth.

8. The combination of the frame provided with the upwardly projecting standard, the carrier movable up and down said standard, means for actuating the carrier, the crimping head mounted to rotate in the carrier, the driven gear on the crimping head, and the driving gear on the carrier, substantially as set forth.

9. The combination of the frame provided with the upwardly projecting standard and having the shell holder, the carrier movable up and down said standard above the shell holder, the stirrup or foot rest having pendent connection with the carrier and serving as a means by which to exert a direct downward strain upon the carrier to move it toward the shell holder, means for elevating and yieldingly upholding the carrier, the crimping head mounted to rotate in the carrier, and means for rotating the crimping head, substantially as set forth.

In testimony whereof I affix my signature in presence of two witnesses.

WM. WAGNER.
